UNITED STATES PATENT OFFICE

ISAAC ROSENHAFT AND ISRAEL HERSKOWITZ, OF NEW YORK, N. Y.

VANITY CASE

Application filed October 2, 1928. Serial No. 309,752.

Our invention relates to vanity cases having a perfume chamber and compartments for holding other cosmetics more or less dry, such as lip sticks and eye-brow pencils. This 5 invention is an improvement over our vanity case as disclosed in Patent #1,490,484, April 15, 1924.

An object of our invention is to provide a simple and compact vanity case which lends 10 itself to ease and cheapness in manufacture.

The case has an inner perfume chamber, or tank, one of whose walls can be flexed inward for ejecting the perfume as desired by the user. The perfume chamber is contained in 15 a larger chamber, which latter chamber is adapted to hold the other cosmetics. The case is also provided with a hinged lid containing a mirror and provided with space for holding a powder puff and compact.

20 We attain these and other objects as will be noted by a further study of the description and drawing, in which:—

Fig. 1 is a front elevation of the vanity case, Fig. 2 is a top plan view, Fig. 3 is an 25 enlarged cross section taken along the line 3—3 of Fig. 1, Fig. 4 is an enlarged sectional plan taken along the line 4—4 of Fig. 1, Fig. 5 is an enlarged sectional plan taken at the same location as Fig. 4, but of a modified form 30 of our device, Fig. 6 is a partial sectional plan showing another modified form, and Fig. 7 is an elevation, looking toward the left in Fig. 1 of one of the removable cosmetic holders.

Main chamber 8 contains the perfume 35 chamber 9 within it. A lug 10 is formed on the top wall of main chamber 8. A tapped hole is provided through lug 10, the top wall of the main chamber 8 and the top wall of perfume chamber 9. Into this hole is screwed 40 the screw portion 11 of tube 12. Tube 12 with its screw portion 11 is fastened to the under side of perfume cap 12. A port 14 leads from tube 12 up through screw portion 11 and to the top of perfume cap 13. Fastened to the 45 front or outer wall of perfume chamber 9, is a button 15 which projects forward through a suitable hole provided in the front or outside wall of main chamber 8. The front wall of perfume chamber 9 is flexible, so that when 50 button 15 is pressed inward, perfume is forced

up through tube 12 and port 14, due to the reduction in volume of the perfume chamber. In order to prevent evaporation when not in use, a knurled stopper disc 16 is provided. Disc 16 is rotatably mounted on pin 17. 55 An opening 18 (Figs. 2 and 3) is provided in said disc at a radial distance away from pin 17 equal to the radial distance of port 14. When disc 16 is turned so that opening 18 comes over the top of port 60 14, perfume may be discharged from perfume chamber 9. When disc 16 is turned so that opening 18 is moved away from the top of port 14, as shown dotted diagonally above and to the left in Fig. 2, the top of port 14 is 65 stopped.

The space not occupied in main chamber 8 by perfume chamber 9 is utilized to hold cosmetics. The cosmetic, usually in the form of a tube or stick, such as shown at 20 or 21 70 (Fig. 1), is forced at its upper end into sleeves 19 of the removable cosmetic holders 22. Suitable holes are provided in the top wall of main chamber 8 for the insertion of sleeves 75 19.

Lid 23 is mounted by means of hinges 24 on the outside of main chamber 8. It contains a mirror 25, held against fiber cushion 26 by means of frame 27. Between mirror 25 and the rear wall of main chamber 8 is a space 80 for holding a powder puff and compact, the latter not being shown.

The modified form shown in Fig. 5, is constructed with front wall 28, of main chamber 8a, flexible. Projecting inward from wall 28 is a stud 29, which, when wall 28 is pressed, forces inward the contacting wall of perfume chamber 9a, ejecting the perfume through tube 12. Only three side walls are shown for perfume chamber 9a, the fourth wall being 90 the back wall of main chamber 8a.

In the modified form shown in Fig. 6, front wall 30, of main chamber 8b is flexible. In this case perfume chamber 9b has a portion of front wall 30 serving as its front wall. Flexing front wall 30 ejects the perfume from perfume chamber 9b through tube 12 (not shown) in a similar manner to the other forms. It is to be observed that perfume chamber 9b is made wider than in the other 100

two forms to enable front wall 30 to be more readily flexed.

Broadly speaking button 15 can be said to form a portion of the front wall of main chamber 8, said portion being loose or movable. It is also to be noted that the portions of walls 28 and 30 opposite the perfume chamber are also movable.

We claim:

10 1. A vanity case comprising a main chamber, a perfume chamber located in said main chamber, said main chamber being wider than the perfume chamber and having its outside wall in the direction of its width provided with a movable portion opposite said perfume chamber for reducing the volume of the perfume chamber and thereby ejecting its perfume.

20 2. A vanity case comprising a main chamber, a perfume chamber located in said main chamber, said perfume chamber having a flexible wall for the ejection of the perfume, said main chamber being wider than the perfume chamber in a direction substantially parallel to said flexible wall, the outside wall of said main chamber running in said direction having a loose portion opposite said flexible wall and fastened to it, said loose portion being movable independently of the rest 30 of said outside wall, enabling pressure on said loose portion to reduce the volume of the perfume chamber and thereby eject its perfume.

35 3. A vanity case comprising a main chamber and a perfume chamber located in said main chamber, said perfume chamber having a flexible wall for the ejection of the perfume, said main chamber being wider than the perfume chamber in a direction substantially parallel to said flexible wall, whereby space for holding cosmetics is left outside of the perfume chamber in the main chamber, said wall being accessible for flexing from the outside of the main chamber.

45 4. A vanity case comprising a main chamber, a perfume chamber, located in an intermediate position in said main chamber, operable from the outside of said main chamber for the ejection of the perfume, said perfume chamber being small enough to leave a space on either side of it in said main chamber sufficiently large to receive a cosmetic.

55 5. A vanity case comprising a main chamber, a perfume chamber, located in said main chamber, operable from the outside of said main chamber for the ejection of the perfume, said perfume chamber being small enough to leave a space outside of it in said main chamber sufficiently large to receive a cosmetic, one of the walls enclosing said space being provided with an opening, and a sleeve open at both ends mounted upon said wall at the opening for supporting a cosmetic holder.

60 6. A vanity case comprising a main chamber, a perfume chamber located in said main

chamber operable from the outside of said main chamber for the ejection of the perfume, said perfume chamber being small enough to leave a space in said main chamber sufficiently large to receive a cosmetic, one of the walls of the main chamber at said space being adapted to admit and to hold a cosmetic.

7. A vanity case comprising a main chamber, a perfume chamber located in said main chamber, said perfume chamber having a flexible wall for the ejection of the perfume, said main chamber being wider than the perfume chamber in a direction substantially parallel to said flexible wall, the outside wall of said main chamber, running in said direction, having an opening therein opposite said flexible wall, and a button fastened to said flexible wall at its inner end and extending loosely through said opening with its outer end substantially flush with the outside of said wall of the main chamber.
